UNITED STATES PATENT OFFICE.

ADOLPH BLACK AND LUTHER E. GREGORY, OF NEW YORK, N. Y.

STATION-INDICATOR.

SPECIFICATION forming part of Letters Patent No. 595,138, dated December 7, 1897.

Application filed February 20, 1897. Serial No. 624,480. (No model.)

To all whom it may concern:

Be it known that we, ADOLPH BLACK and LUTHER E. GREGORY, citizens of the United States, residing at New York, in the county 5 and State of New York, have invented new and useful Improvements in Station-Indicators, of which the following is a specification.

By means of this invention streets or stations—such as those being approached, for 10 example, by a car or conveyance—can be indicated automatically or have their designations exposed to view of passengers; and the invention relates to novel arrangements by which practically uniform and accurate actuation of the indicating-strip can be secured, as also to other features set forth in the following specification and claims and illustrated 15 in the annexed drawings, in which—

Figure 1 is a sectional side elevation of a 20 station-indicator. Fig. 2 is a sectional front elevation of Fig. 1. Fig. 3 is a detail side view of a reversing gear or train in different position than in Fig. 1. Fig. 4 is a plan view of Fig. 3. Fig. 5 shows a driving mechanism 25 for the worm-shaft.

A casing or box U, adapted to be secured at a suitable place, as inside a railroad-car, has a sight or opening V for exposing to view the required station or information on the 30 traveling strip K. Into this box U extends a rotary worm-shaft C, actuated by suitable gearing or connection, as with a car-wheel or auxiliary wheel. This worm-shaft C rotates gear E on shaft D, and gear F is connected 35 to or rotates with gear E.

On shaft D swings the arm R of a reversing gear or mechanism, said arm R carrying a rotary gear G, meshing with gear F. To arm R is jointed a link 1, jointed to a link 2, 40 having a pivot or support 3 on a side or suitable part of the case U. The links 1 and 2 form what may be called a "toggle-joint." At the joint of links 1 and 2 is mounted the rotary gear H, meshing with gear G. The 45 arm R projects through a slot or opening W in the case, and by swinging arm R to the position shown in Fig. 1 gear H is made to mesh with gear I to rotate the latter in one direction. The gear G is now out of mesh 50 with gear I. When the arm R is moved to the position shown in Fig. 3, the wheel H is

moved out of mesh with gear I and the gear G is moved into mesh with gear I, so that the latter is rotated in the opposite direction, gear H now running idle. By moving 55 arm R to a position intermediate between that shown in Figs. 1 and 3, so that both gears G and H are out of mesh with gear I, the latter is left to stand still.

The gear I is fixed to shaft 4, to which is 60 fixed a driving-drum J, and gear I meshes with gear L, fixed to shaft 5, to which is fixed a smoothing-drum O. The drums J O, rotating at equal circumferential speeds, feed the strip K in one direction or another. 65

The driving-gear I meshes into gear M, which in its turn meshes with gear N, so that gears M and N rotate in opposite directions. These gears M and N are mounted loosely on shafts 6 and 7, and each gear has fixed thereto 70 an eccentric stud 8 and 9, to each of which is fixed an end of a coiled spring, as 10 and 11, respectively, having their other ends fixed to shafts 6 and 7. To these shafts 6 and 7 are fixed the drums P and Q, on one of which 75 the strip K is wound while unwinding from the other, and vice versa.

The springs 10 and 11, it is noticed, coil about the shafts 6 and 7 in the same direction, while the gears M and N rotate in opposite directions. The strip K passes over 80 guide-roller T in traveling to or from drum P.

To make the strip travel in the direction of arrow 12, Fig. 1, the drum P, with gear N, rotates in the direction of arrow 13, and the 85 drum Q, with gear M, rotates in the direction of arrow 14. This rotation of gear N tends to cause an unwinding or slackening of the spring 11, so as to ease the delivery of ribbon K from the drum P, while the rotation of gear 90 M tends to wind up or tighten spring 10 to cause an efficient take-up of ribbon K by drum Q.

When gears G and H are out of mesh with gear I, the drum J, with strip K, can be set or 95 adjusted by crank or handle S, Fig. 2.

The drum or rollers P and Q may be considered carrying-rollers, since they carry or support the strip or ribbon K in readiness to be delivered to or taken from roller or driv- 100 ing-drum J.

Jointed to reversing-arm R at 16, Figs. 1

and 3, is an arm 17, the free end of which is forked to straddle shaft 5, as seen in Fig. 3. Said free or forked end is cam-shaped, having its central part 18 high or wide, as seen 5 in Fig. 4, and narrowing to the end portions 19. These cam portions 18 19 as the arms R and 17 are shifted move back and forth in the groove or way 20 of the friction-disk 21, sitting loosely on shaft 5, but prevented from 10 turning—as, for example, by the engagement of cam part 18 into said groove 20. When the arm R is shifted to one extremity or another of its throw, one or another of the low cam parts 19 is between the disk 21 and the 15 collar 22, sitting loosely on shaft 5 and exposed to the action or pressure of spring 23. When, however, the arm R is in intermediate position to hold both the gears G and H out of mesh with gear I, the high part 18 of 20 the cam 18 19 is moved between the collar 22 and the disk or brake 21, so as to press the latter against gear L and prevent the latter, with drum O and strip K, as also drum J, from moving. The strip K is also thus guarded 25 against accidental displacement or shifting.

The pin or fulcrum 24 supports a handle or lever 25, sufficiently loose or free to allow this lever to be moved for taking or moving the spring-pressed collar 22 away from cam part 30 18 when said cam, with arm R, is in middle or intermediate position, if the gear L is at such time to be temporarily freed, as when setting by the handle or crank S. The handle 25 projects out through a slot or opening 26 in 35 case U, so as to be conveniently reached.

The shaft 4 is shown supporting swinging arms 27 concentrically with the driving-drum, Figs. 2 and 3, said arms carrying spring-boxes for the shaft 5 of drum O, so that the latter 40 is held in proper contact with the drum J or strip K.

The shaft C is shown actuating a gear 28, Fig. 1, having an eccentric or crank pin 29, reciprocating link 30, jointed to arm 31, swinging 45 on shaft 32. This arm 31 carries a pawl 33, engaging ratchet 34 to rotate the latter with shaft 32. This shaft 32 being given a step-by-step or gradual rotation is made to successively expose leaves or advertising 50 faces 35 through sight V'. The ratchet 34 can be secured against retrograde motion by a stop-pawl 36, or said stop-pawl may form or be part of a hammer or sounding device for announcing an actuation of the advertising 55 device.

The gears F and I may be considered actuating or driving gears, having the interposed pair of connecting-gears G and H.

By having the slot 20 deepened toward the 60 periphery of disk 21, the cam part 18 enters such deepened slot part when said cam is in releasing position and enables the disk or brake to move from gear L to free the latter, while, when in central position and pressing 65 on the high or central part of slot 20, the cam 18 holds the brake 21 in action, or in place of the slot 20 being curved the face of collar 22,

contacting with cam 18, might be suitably curved or convexed.

As the ordinary car-wheels are braked or 70 at times interfered with, the shaft C is advantageously worked from a separate wheel or wheels A, running independently of the supporting-wheels of the car, as seen in Fig. 5.

As the crank-pin oscillates the links 30 and 75 31, no matter whether the wheel 28 rotates in one direction or another, the advertising device or leaves will always be moved forward.

If the car at the end of the trip is not turned 80 around, so that on the return trip the end of the car which before was the rear end now forms the front end, the arm R need not be shifted. If, however, the car should, for example, run around a loop to shift to the return-track, the reversing-gear will have to be 85 shifted by lever R.

What we claim as new, and desire to secure by Letters Patent, is—

1. A driving drum or roller and carrying-rollers, combined with actuating-springs for 90 the carrying-rollers, and winding-gears for the springs loosely connected to the carrying-rollers each of said springs being attached at at one end to one of the winding-gears and at its other end to the corresponding carrying- 95 roller, substantially as described.

2. A driving drum or roller and carrying-rollers, combined with a driving-gear for the driving-roller, actuating-springs for the carrying-rollers, and spring winding-gears loosely 100 connected to the carrying-rollers and actuated by the gear of the driving-roller substantially as described.

3. A driving drum or roller and a pair of 105 actuating or driving gears for the roller, combined with a pair of connecting-gears between the actuating-gears, a movable arm for supporting one of the connecting-gears in permanent engagement with one of the driving- 110 gears and for carrying said connecting-gear toward and from the second driving-gear, and a toggle joint or links actuated by the movable arm for carrying the second connecting-gear toward and from said second driving-gear while supporting said second connecting- 115 gear in permanent engagement with the first connecting-gear substantially as described.

4. A driving drum or roller and a pair of 120 actuating or driving gears for the roller, combined with a pair of connecting-gears between the actuating-gears, a movable arm for supporting one of the connecting-gears in permanent engagement with one of the driving- 125 gears and for carrying said connecting-gear toward and from the second driving-gear, a 130 toggle joint or links actuated by the movable arm for carrying the second connecting-gear toward and from said second driving-gear while supporting said second connecting-gear in permanent engagement with the first connecting-gear, a brake, and a cam made to hold the brake in action when the connecting-gears are in intermediate position or disengaged from the second driving-gear and to 135

free the brake when either of the connecting-gears is in engagement with the second driving-gear substantially as described.

5. A driving drum or roller and a pair of actuating or driving gears for the roller, combined with a pair of connecting-gears between the actuating-gears, a movable arm for supporting one of the connecting-gears in permanent engagement with one of the driving-gears and for carrying said connecting-gear toward and from the second driving-gear, a toggle joint or links actuated by the movable arm for carrying the second connecting-gear toward and from said second driving-gear while supporting said second connecting-gear in permanent engagement with the first connecting-gear, a brake, a cam made to hold the brake in action when the connecting-gears are in intermediate position or disengaged from the second driving-gear and to free the brake when either of the connecting-gears is in engagement with the second driving-gear, a spring for holding the cam toward the brake and a releasing or retracting han-

dle or lever for the spring substantially as described. 25

6. A driving drum or roller, carrying-rollers, and a train of gears made to actuate said rollers, combined with a driving-shaft for said gears, a gear-wheel actuated by said driving-shaft, a link eccentrically pivoted at one end to said gear-wheel and at its other end pivotally connected to the end of an arm journaled on a shaft, a series of advertising-leaves carried by said shaft, a ratchet fixed 30 on the shaft, and a pawl carried by the said arm and engaging said ratchet to impart to the shaft a step-by-step rotation, to successively expose the leaves, substantially as described. 35

In testimony whereof we have hereunto set our hands in the presence of two subscribing witnesses. 40
